UNITED STATES PATENT OFFICE.

GEORGE SAMUEL BAKER, OF WILLESDEN JUNCTION, ENGLAND.

BAKER'S OVEN.

SPECIFICATION forming part of Letters Patent No. 768,719, dated August 30, 1904.

Application filed February 15, 1904. Serial No. 193,684. (No model.)

To all whom it may concern:

Be it known that I, GEORGE SAMUEL BAKER, a subject of the King of England, residing at Willesden Junction, England, have invented 5 certain new and useful Improvements in Bakers' Ovens, of which the following is a specification.

This invention relates to bakers' ovens heated by Perkins's tubes; and the object of the 10 invention is to provide means for enabling such tubes to be heated to a higher temperature when a higher temperature is required.

The annexed drawings illustrate the invention as applied to a double-decker draw-plate 15 oven with rear firing, Figure 1 being a vertical section of such an improved oven; Fig. 2, a cross-section thereof on line 2 2, Fig. 1; Fig. 3, a cross-section on line 3 3 of Fig. 1; Figs. 4, 5, and 6, horizontal sections on lines 20 4 4, 5 5, and 6 6 of Fig. 1, respectively; and Fig. 7, a similar section on line 6 6, Fig. 1, showing a modified arrangement of upper flue.

A is the structure of the oven; B B', the upper and lower oven-chambers.

C C' are draw-plates; D D oven-doors.

E E' E² E³ are sets of Perkins's tubes; F F' combustion-chambers of the furnace.

E' is a wide vertical flue leading directly 30 upward in the rear wall of the oven from the combustion-chambers F F' to the flue G, with which it has controllable communication through the damper H. Into this flue E' the

closed ends of the tubes E E' E² E³ project to be heated in the known manner. In the present invention a branch flue J leads out at one or both sides from the lower part of flue E' to a chamber K, Fig. 4, under the front part of the lower oven, and thence a flue L leads laterally to the side of the oven, where it ascends at L' to the top of the oven, whence it is carried at L² obliquely, Fig. 6, or in a serpentine course, Fig. 7, into the flue G, before mentioned, which leads to the shaft.

M is a damper in flue G.

The chamber K heats the tubes E² and E³ immediately above it, and thus brings these tubes to a higher temperature.

I claim—

A baker's oven having in combination with 50 oven-chambers, Perkins's tubes and furnace, a damper-controlled flue rising directly from said furnace to the shaft-flue for heating the ends of said tubes, a chamber beneath said tubes in the base of the oven near the end remote from the furnace, a branch flue from the furnace to said chamber, a rising flue from said chamber in the side of the oven and a return-flue from said rising flue to the shaft-flue for the purpose set forth.

In witness whereof I have signed this specification in the presence of two witnesses.

GEORGE SAMUEL BAKER.

Witnesses:

H. D. JAMESON,
A. NUTTING.
